EDWIN METCALF, OF NORRISTOWN, PENNSYLVANIA.

Specification forming part of Design No. 5,941, dated June 18, 1872.

SPECIFICATION.

Specification describing a new Design for a Picture, titled the Life of Christ, designed by EDWIN METCALF, of Norristown, in the county of Montgomery and State of Pennsylvania.

The nature of my design is fully represented in the accompanying photographic illustration. The original picture was made exclusively with a pen, after four years' close labor and study. No time or expense has been spared to secure this to be the perfection of artistic beauty and Christian art. It was designed to show to churches, Sunday-schools, Bible-classes, Young Men's Christian Associations, and all religious societies the principal transactions of Jesus Christ during his stay on earth, from his Annunciation to his first appearance to Mary Magdalene, after his ascension. Also embracing the twelve apostles, two children in prayer, angels, the Lord's prayer in four languages, the Bible, the ten commandments, the blessings for the afflicted and woes for the wicked, Jerusalem, Bethlehem, Bethany, with many other rare and emblematic designs; altogether forming a view near Jerusalem of seven and a half miles.

To enable persons skilled in the art to construct and use the same, I prefer to have them photographed in three different sizes; but they can be lithographed, and engraved on steel, copper, wood, &c., as may be elected.

A represents the Scriptures, (2 Tim. iii. 15, 16.) These terms are applied to the inspired writings contained in the Old and New Testaments. They are also called the Bible, or the Book, in distinction from all other books, (Mark xv. 28; Gal. iii. 8.)

B represents Mary.

C represents Joseph. Nothing is said in Scriptures of the early history of either Mary or Joseph. They are presented to us as poor in circumstances, but believers in the religion of their fathers, waiting for the "consolation of Israel" and the fulfillment of prophecy. Mary was the virgin mother of Jesus, yet she is nowhere named in Scripture the Virgin Mary.

D represents the Annunciation, (Luke i. 35.) "And the angel answered and said unto her, the Holy Ghost shall come upon thee, and the power of the Highest shall overshadow thee;

therefore that holy thing which shall be born of thee shall be called the Son of God."

E represents the Birth of Christ, (Matt. ii. 11.) "And when they were come into the house they saw the young child, with Mary his mother, and fell down and worshipped him; and when they had opened their treasures, they presented unto him gifts: gold, and frankincense, and myrrh," (Ps. lxxii. 10; Isa. ix. 6.)

F represents the Bust of Jesus, (Matt. i. 21.) "And she shall bring forth a son, and thou shalt call his name Jesus, for he shall save his people from their sins," (Eph. ii. 10; Luke ii. 21; Matt. xxvi. 63; Mark viii. 29; xiv. 61; John i. 20, 25, 41; vi. 69; vii. 41; x. 24; xi. 27; xx. 31.)

G represents Childhood, (Micah v. 2.) "But thou Bethlehem Ephratah, though thou be little among the thousands of Judah, yet out of thee shall he come forth unto me that is to be ruler in Israel," (Matt. ii. 6; Luke ii. 14; John vii. 42.)

H represents the Baptism of Christ, (Matt. iii. 13.) "Then cometh Jesus from Galilee to Jordan to be baptized of him," (Matt. iii. 14, 15, 16; Mark i. 10.)

I, Sermon on the Mount, (Matt. v. 1.) "And seeing the multitudes, he went up into a mountain; and when he was set, his disciples came unto him," (Matt. viii. 1; Luke vi. 17-19.)

J, Transfiguration, (Matt. xvii. 1-13.) "And after six days Jesus taketh Peter, James, and John his brother, and bringeth them up into a high mountain apart, and was transfigured before them."

K, Last Supper, (Matt. xvii. 26-28.) "And as they were eating, Jesus took bread and blessed it, and brake it, and gave to the disciples, and said: Take, eat, this is my body," (1 Cor. xi. 20-23; John vi. 35; Matt. iv. 6, 11; Gen. ii. 3.)

L, Scourging Jesus, (Matt. xxvii. 26.) "Then released he Barabbas unto them; and when he had scourged Jesus, he delivered him to be crucified," (Isa. liii. 5; John xix. 1.)

M, Crucifixion, (Matt. xxvii. 22.) "Pilate saith unto them, what shall I do, then, with Jesus, which is called Christ? They all say unto him, let him be crucified," (Mark xv. 16; Luke xxiii. 26; John xix. 16-30.)

N, Resurrection, (Matt. xxviii. 5, 6.) "And the angel answered and said unto them, fear not ye, for I know that ye seek Jesus, which was crucified. He is not here; for he is risen," (Mark xvi. 1-11; Luke xxiv. 1-12; John xx. 1-18.)

O, Ascension, (Mark xvi. 15-19.) "So then, after the Lord had spoken unto them, he was received up into Heaven, and a cloud received him out of their sight," (Luke xxiv. 44, 45-51; Acts i. 4-11; 1 Cor. xv. 15, 17.)

P, Christ first appeared to Mary Magdalene, (Mark xvi. 9.) "Now, when Jesus was risen, early the first day of the week, he appeared first to Mary Magdalene, out of whom he had cast seven devils," (Luke viii. 2; John xx. 14; Matt. xxvii. 55, 56.)

Twelve Apostles.

Q, John the Baptist, (Matt. iii. 1.) The prophet and forerunner of our Saviour, and the Elias of the New Testament. He was the son of Zacharias, the aged priest, and Elizabeth, (Luke i. 13,) and was born about six months before Christ. His birth and work were predicted by the angel Gabriel, (Luke i. 5-15,) and by Isaiah, (Isa. xi. 3,) and by Malachi, (Mal. iv. 5.)

R, Peter—Rock—(John i. 40,) the son of Jonas or Jona; hence called Simon Bar-Jona, (Matt. xvi. 17.) He was a brother of Andrew, and was a native of Bethsaida. His original name was Simon or Simeon; the name Cephas (a Syriac word, signifying a rock, and in Latin Petra) was given him when he was called to the apostleship, (John i. 42; comp. Matt. xvi. 18; viii. 14; Mark i. 29; Luke iv. 38; v. 1-3.)

S, Judas Iscariot (Matt. x. 4) was one of the twelve chosen disciples of our Lord. Nothing is certainly known of his birth-place or parentage. It is supposed by some that the word Iscariot signifies man of Carioth, a small town on the east side of Jordan. He is called the son of Simon, (John vi. 71.)

T, Andrew, (John i. 40,) the son of James and brother of Simon Peter, was a native of Bethsaida, in Galilee, and originally a disciple of John the Baptist, whom he left to follow our Saviour.

U, James the Elder, (Matt. iv. 21,) a son of Zebedee and Salome, and brother of John the Evangelist. He was put to death by Herod A. D. 42-44, (Acts xii. 2; Mark xv. 40.)

V, Bartholomew, son of Tholomaeus, or Tolmai, (Matt. x. 3,) is supposed to be the same person who is also called Nathaniel.

W, Thomas, (John xx. 24,) one of the twelve apostles, was also called Didymus, "the twin," (John xi. 16; xiv. 5; xx. 20-29.)

X, James the Less. This James is probably intended, in Gal. i. 19, by the "Lord's brother," (Matt. xiii. 55; Mark vi. 3.) He was first cousin to our Saviour, (John xix. 25.)

Y, Philip (John i. 43) was a native of Bethsaida, and a firm believer in the Messiahship of Christ, (John i. 45; Acts xxi. 8, 9; xxii. 3-5; Luke iii. 1; Matt. xiv. 3.)

Z, Matthew—God's gift—(Matt. ix. 9,) called also "Levi," (Mark ii. 14,) was a native of Galilee, and, though a Jew, was employed as tax-gatherer under the provincial government of Judea, (Mark ii. 15; Acts i. 13.)

a¹, Thaddeus (Jude i. 1) was one of the apostles and brother of James the Less. He is called Judas, (Matt. xiii. 55; John xiv. 22; Acts i. 13,) and elsewhere Lebbeus (Matt. x. 3,) and Thaddeus. Lebbeus and Thaddeus are synonyms, (Mark iii. 18.)

b¹, Simon, the Canaanite, (Matt. x. 4,) or Simon Zelotes, or the Zealot, (Acts i. 13; Luke vi. 15.)

c¹c¹, Ten Commandments. These are printed in the old English text hand, on the representation of two tables of stone, (Ex. xx. 3-17; Deut. v. 22.) "These words the Lord spake unto your assembly in the mount, out of the midst of the fire, of the cloud, and of the thick darkness, with a great voice; and he added no more; and he wrote them on two tables of stone."

d¹ and e¹ are two children, brother and sister, taken from life, kneeling in prayer, (Matt. vi. 9.) "After this manner, therefore, pray ye: Our Father which art in Heaven," (Matt. xix. 14.) But Jesus said: "Suffer little children, and forbid them not, to come unto me, for of such is the kingdom of Heaven," (Matt. xviii. 3; Ps. cxxxii. 2; Luke xviii. 16; 1 Cor. xiv. 20; 1 Peter ii. 2.)

f¹, Two angels carrying an ornamented roll containing the blessings for the afflicted, printed in the addressing alphabet, from Luke vi. 20-23.

g¹, Two angels carrying an ornamented roll containing the woes for the wicked, printed in the same as f¹, from Luke vi. 24-26. Angel—This word in the Greek and Hebrew languages signifies a messenger (2 Sam. ii. 5; Luke vii. 24, and ix. 52) of their number, (1 Kings xxii. 19; Ps. lxviii. 17; Dan. vii. 10; Matt. xxvi. 53; Luke xi. 9-14; 1 Cor. iv. 9; Heb. xii. 22, &c.)

h¹, Angel. i¹, Angel bearing the Lord's prayer, k¹k¹, in the English language, (Matt. vi. 9,) printed on the representation of a roll of paper. l¹, The German Lord's prayer, printed in the formation of a heart, in the center of the English Lord's prayer. The border of the heart is the 97th Psalm, written in the Hebrew language. m¹, The French Lord's prayer. n¹, The Spanish Lord's prayer, both of which are printed on the surface of the representation of two olive-leaves, bordered with flowers and suspended from the scroll-work o¹o¹, which also contains the bust of Christ, F.

p¹p¹, Jerusalem; is situated in 31° 50' north latitude, and 35° 20' east longitude from Greenwich. The first notice of the site is probably under the appellation "The land of Moriah," to which Abraham was divinely commanded to go for the purpose of presenting Isaac as a burnt offering on one of its mountains.

r¹, Bethlehem—House of bread—(Gen. xxxv. 19,) called also Bethlehem Ephratah, (Mic. v. 2,) was the birthplace of David, (Luke ii. 4-11,) and was still more sacred and celebrated as the birth-place of the Redeemer, (Matt. ii. 1; Luke ii. 4, 6.)

s¹, Bethany—House of dates—(Mark xi. 1,) a village on the southeast side of the Mount of Olives, about two miles from Jerusalem. It was the residence of Lazarus and his sisters, (John xi. 1.) Christ often resorted thither, (Matt. xxi. 17; xxvi. 6; Mark xi. 11, 12; xiv. 3; John xi. 1, 46, and xii. 1-3.)

t¹ t¹ t¹ t¹ t¹ t¹ is a wreath formed out of the vine and flower of the Passion vine, which means, in the language of flowers, faith.

u¹ u¹ v¹ v¹ w¹ w¹ x¹ x¹ y¹ y¹ are representations of white silk bands, twisted in the wreath t¹ t¹ t¹ t¹ t¹, with pieces printed on them, selected from the Bible, to suit the design of the picture.

Having thus described my design for a picture (titled the Life of Christ) as minutely as possible, I will therefore state my claim.

I do not claim any one part separately, but I do claim as my invention, and desire to secure by Letters Patent—

The arrangement and combination of the whole figures represented in the photograph illustration, forming a picture, and titled the Life of Christ, substantially as and for the purpose hereinbefore set forth and described.
